UNITED STATES PATENT OFFICE

J. HOWARD MENDENHALL AND THOMAS T. SHOAF, OF SAN FRANCISCO, CALIFORNIA

SUSPENDED CAMP COOLER

Application filed September 16, 1931. Serial No. 563,204.

Our invention relates to improvements in suspended camp coolers, and it consists of the combinations, constructions and arrangements hereinafter described and claimed.

5 An object of our invention is to provide a suspended camp cooler which is collapsible so as to be packed in a small space when not in use, and which is designed to be cooled by air or water. The device has adjustable shelves 10 and it is entirely enclosed by cloth which protects the food carried by the device from insects, birds and animals.

The device is extremely simple in construction, and is particularly designed for 15 automobile campers.

Other objects and advantages will appear in the following specification, and the novel features of the device will be particularly pointed out in the appended claims.

20 Our invention is illustrated in the accompanying drawings forming a part of this application, in which

Figure 1 is a perspective view of the device;

25 Figure 2 is a longitudinal section through the water container;

Figure 3 is a vertical transverse section through the device;

Figure 4 is a top plan view of one of the 30 shelves;

Figure 5 is a section along the line 5—5 of Figure 1;

Figure 6 shows a shelf supporting member; 35 and

Figure 7 is a sectional view along the line 7—7 of Figure 1.

In carrying out our invention we provide a rigid bottom 1, rigid shelves 2, and a rigid 40 top 3, the bottom 1, the shelves 2, and the top 3 having openings 4 therein for permitting supporting chains 5 to pass therethrough. The bottom 1 has bars 6 that extend across the openings 4 and through the 45 lowermost links of the chains 5. The bars 6

are secured to the bottom 1 and in this way the bottom is supported by the chains.

In Figure 6, we show supporting members 7 for the shelves 2 and the top 3. Each supporting member has its ends formed into eyelets 8 with tongues 9 that extend along the members in the manner shown. The tongues are passed through the links of the chains 5 and the shelves 2 and the top 3 rest upon the members 7. The members 7 may be disposed in any position desired along the chains 5 and in this way the shelves are adjustable. It is obvious that as many shelves as desired may also be used.

The tops of the chains 5 are connected to a supporting member 10 (see Figure 1) having an eyelet 11 formed therein. The top of the member 10 has a hook 12 designed to be secured to any support such as that indicated by the dotted lines 13.

A flexible cloth wall 14 (see Figures 1 and 2) is provided and this wall has its bottom and top edges attached to the bottom 1 and the top 3. Figure 7 shows how the edges of the cloth are passed around a strip 15, which in turn is nailed or otherwise secured to the bottom 1. The top edge of the wall 14 is secured to the top 3 in the same manner.

The wall 14 has an opening 16 (see Figure 1) that extends from the top 3 to the bottom 1. A cloth flap 17 is secured to the top 3 and has a bar 18 (see Figure 5) that extends across its bottom and is receivable in clips 19 carried by the bottom 1. A handle 20 is secured to the bar 18.

80 Zippers 21 are employed for securing the flap 17 to the wall 14 along the entire vertical edges of the flap and wall. When the zippers are closed as shown in Figure 1 the interior of the cooler is protected from insects, birds and animals.

85 We provide a cooling means for the device and this comprises a water container 22 having flexible walls and being disposed on the top 3. Splash plates 23 extend transversely 90

across the container 22 and Figure 2 shows how the bottom edges 24 of these plates are spaced above the bottom 25 of the container 22. The splash plates are flexible.

5 A wick 26 preferably circular in cross section is passed beneath the bottom edges of the splash plates 23 and has its ends passed over the ends of the container 22 and secured to the wall 14. Other wicks 27, similar to 10 the wick 26, are passed beneath the wick 26 and over the sides of the container 22 and have their ends secured to the wall 14 and the door flap 17. Water 28 is placed in the 15 container 22 and the wicks will convey this water to the wall 14 and the door flap 17 by capillary attraction. In this way the wall 14 and the door are maintained in a moist condition, and the evaporation of this water will keep the interior of the device cool.

20 When packing the device the bottom 1 and the top 3 may be moved toward each other and the wall 14, the flap 17, and the chains 5 will permit the device to be collapsed into a small space. The container 22 will also 25 collapse.

This device may be cleansed by turning the unit inside out after removing the shelves between the bottom and the top.

30 Metal pipes 28' enclose the portions of the wicks that extend between the water in the container and the wall 14. These pipes are hooked over the edges of the container wall and prevent evaporation of the water from the wicks. The pipes may be disposed inside 35 the container when the device is collapsed.

The flexible walls of the container 22 are supported by being attached to the chains 5.

40 While we have shown only the preferred form of our invention, it should be understood that various changes or modifications may be made within the scope of the appended claims without departing from the spirit of the invention.

We claim:

45 1. A collapsible cooler comprising a base and a top, flexible supporting members extending from the base and passing through the top, a flexible wall connecting the base and the top, a portion of the wall constituting 50 a door, shelves adjustably connected to the supporting members, clips carried by the base, a bar carried by the bottom of the door, and being receivable by the clips, and fastening means for securing the entire lengths of 55 the side edges of the door to the edges of the flexible wall.

2. In a collapsible cooler, a water container having strips extending thereacross with their lower edges spaced above the bottom 60 of the container, a wick passed beneath the strips and having its ends overhanging the container, and other wicks extending beneath the first wick and having their ends overhanging the container.

65 3. In a collapsible cooler, a rigid top and

bottom, clips carried by said bottom, a cloth wall extending between the two and having an opening extending the height of the wall, a flexible door secured to the top and having a bar extending across its bottom and being receivable in the clips, and fastening means securing the sides of the door to the edges of the opening.

4. In a collapsible cooler, a bottom and top, flexible members supporting the bottom and extending through the top, shelves having openings for receiving the members, and bars adjustably secured to the flexible members for supporting the shelves and top.
